UNITED STATES PATENT OFFICE.

FRANK B. COMINS, OF NEWTON, MASSACHUSETTS, ASSIGNOR TO AMERICAN MOISTEN-
ING COMPANY, OF PROVIDENCE, RHODE ISLAND, A CORPORATION OF MAINE.

ATOMIZING MEANS.

Application filed August 7, 1923. Serial No. 656,242.

This invention relates to atomizing means. More particularly it relates to an improved fog generator for a centrifugal humidifier. In such machines water is delivered to the 5 surface of a rotor which films and throws it by centrifugal force against fixed impact plates distributed about the edge of the rotor. The impact against these plates breaks up the film into minute particles which may either float away like a fog or, as is most 10 common, be forcibly expelled from the humidifier by a blast of air provided for that purpose.

Spatter plates or fog generators to be most 15 efficient should serve a double function. They must not only cause pulverization of the liquid, but they must entrap the larger particles which are too heavy for the air to carry until complete absorption, for, if 20 such particles are permitted to leave the humidifier casing, they soon settle upon whatever is below and become a source of annoyance to persons, and of damage to property, upon which they fall. It is to reduce 25 this evil that many such humidifiers heretofore built have had to be provided with huge projecting pans to catch the shower of drops that would otherwise fall into the room.

30 It is accordingly an aim of the present invention to provide plates, which shall primarily break up the liquid film into as fine particles as is possible, and which shall secondarily entrap and eliminate, from the fog 35 generated, such over-large globules as do occur, and conduct them out of the zone of the air blast. And withal it is a feature to provide these plates in a form that is economical 40 to make and easy to assemble in series, which series may be incorporated in the humidifier as single or multiple rows as desired.

The individual plates are made by stamping 45 a washer-like ring from thin sheet metal and then in the same stamping operation, or by a subsequent cutting, dividing these rings into semi-annular pieces. The latter are then mounted, with their plane surfaces parallel, upon and preferably perpendicular to 50 a binder or base rod which when installed has the form of a circle of slightly larger diameter than that of the delivery edge of the rotor. This base rod is held by plate-legs a short distance above the pan or bot- 55 tom of the humidifier casing, to provide

space for drainage, and may be provided with a reinforcing strip having notches for 60 positioning and steadyng the impact plates, which are secured to the rod near one of their diametrical edges so that the greater portion of each is upstanding from the rod, in direction away from the pan of the casing. They may be set with their thin edges radially toward the rotor, or may be inclined there- 65 to to make any angle desired to the direction of flight of the liquid film as it leaves the rotor. In the embodiment shown the impact plates or blades are set radially, with their outside circular edges toward the rotor. They might be reversed to have their inner 70 circular edges toward the rotor; but for ordinary uses the arrangement illustrated is preferable. The plates and rotor may be relatively positioned with the edge of the latter at, above, or below the middle of the 75 plates, but it has been found desirable to have the film strike the plates a little above their centers against the upper half of their flat surfaces. At the moment of impact the liquid is pulverized, the finest and lightest 80 particles immediately floating outward and upward from the plates, and being picked up and carried along by the air current. The heavier particles rebound from the 85 plate which forms them, in directions outward and somewhat upward which bring them for the most part against the upper portions of the next adjacent plates of the series which curve outward and upward 90 across their rebound path. Since they strike such a plate on the side opposite to that against which the film is being delivered, they are not blown or knocked off but either 95 rebound again, in smaller fragments, or run down that side of the plate and drop to the pan where they drain away harmlessly.

If desired another circular row of impact plates may be arranged outside of the row which is next to the rotor's edge, in staggered relation to the plates of the first row. 100 Such a secondary line of plates aids further in the elimination of the heavy particles and also spatters any portion of the film which passes through the spaces in the inner row. The double arrangement is an improvement over the impact plates heretofore made entirely circular, as separate washers, or that form in which a continuous helical thin strip has been mounted upon a base rod. This improvement makes a portion of a plate in the 105 110

outer row more effective in pulverizing the film, because nearer to the rotor; and it places the portion of the outer plate against which the heavy particles strike at a greater distance from their place of formation, in a position to more surely entrap them in their rebound.

It is intended that the patent shall cover, by suitable expression in the appended 10 claims, whatever features of patentable novelty exist in the invention disclosed.

In the accompanying drawings:

Figure 1 shows, in elevation, and partly in section, humidifying apparatus embodying the improved fog generator of the invention;

Figure 2 is an elevation of a portion on a larger scale, showing the details of a single row of the improved spatter plates;

20 Figure 3 is a plan thereof;

Figure 4 is a view like Figure 2, but showing a double row of spatter plates; and

Figure 5 is a plan of the same.

Referring to the drawings, the humidifier 25 comprises a rotor 10 to the under side of which water is delivered by any suitable means from a well 12 fed by the supply pipe 14, and by which rotor the water is filmed and thrown centrifugally outward against 30 a series of impact plates 16 which cause it to break up into fine particles. These particles float in air and so form a fog which is distributed from the apparatus by a blast of air generated in the upper portion of the 35 humidifier and driven downward and outward past the impact plates. A motor 18 propels the shaft on which both the air fan and the rotor are mounted.

The impact plates individually are half 40 round flat pieces, which may be stamped from sheet metal at minimum cost. Near one end, the outer curved edge 16^a of each plate is fastened to a base rod 18, as by soldering, and to hold them more securely 45 they may also be set into notches of, and be soldered to, a thin fin 20 provided on the rod. As shown the plates are arranged with their flat sides parallel, and with their longer and outer peripheral edges 16^a radially toward 50 the axis of the rotor, but this positioning may be varied as desired to set the blades at any angle to the direction of flight of the film from the rotor's edge. The base rod and fin are supported a short distance above 55 the pan bottom 22 by plate legs 24 so that any water flowing down the pan will not be obstructed.

In operation the rotor is adjusted so that 60 the film strikes the flat sides of the plates a little above the middle. Upon impact the film is broken up and the liquid pulverized into minute particles which for the most part are picked up by the air current, which 65 driven downward by a fan within casing 19, is deflected by the top surface of the rotor

through the upper portion of the spaces between the plates. In practice, it is found that in striking the plates, a number of heavy, large particles of liquid are formed, which should be eliminated from the fog 70 stream before it leaves the humidifier and enters the surrounding atmosphere. As the liquid strikes the flat side of a plate, the globules formed rebound in varying directions away from the place of impact. Any 75 large particles which rebound downward in the general direction of arrow 1 under the edge of the rotor settle upon the pan 22. Those which rebound downward and outward in the general direction of arrow 2 do 80 the same, for the force of the air current just ahead of the plates is substantially above the center thereof and does not pick up the particles falling downward. Those 85 that fly upward and inward over the rotor in the general direction of arrow 3 into the very teeth of the air blast, are borne away by it or are driven back against the plates and their pulverization completed. Those 90 heavy particles which rebound outward and upward in the general direction of arrow 4 are the ones which ordinarily are carried outside of the casing by the air current, whence they fall upon whatever is below. It is these particular heavy particles which 95 must be entrapped, and the present invention accomplishes this by providing a barrier in their path close by their place of formation. That is, the upper portion 16^b of one impact plate, as it curves outward and upward from the rotor's edge, crosses the path of those particles which in their rebound tend to fly upward and outward. When 100 these heavy particles strike the side of the next plate, which faces opposite to that side 105 against which the film is originally impinging, they may adhere thereto long enough for them to run down the plate out of the air draft whence they ultimately drop from the base rod into the pan. This extension part 110 of the impact plate therefore constitutes an eliminator plate.

Where it is desired to use a particularly strong blast for driving the humidified air some distance away from the humidifier, 115 there may be provided a second row of eliminator plates 116 as shown in Figures 4 and 5, just outside the row that is next to the rotor's edge. This outer row is a duplicate 120 of the inner one and functions in like manner. Preferably it is arranged with its blades opposite the spaces of the inner row (Figure 5) to present obstacles to any portion of the film dodging through the inner spaces. These outer plates also catch any 125 large particles driven outward too fast to impinge on the upper portions 16^b of the inner row, so that even in a high duty blast, the humidified air is discharged practically 130 free of oversized globules.

The impact plates of the invention may be combined with any form of rotor, and may either be used alone, as heretofore described, or may be used in cooperation with 5 any of the types of impact blades now on the market.

I claim as my invention:

1. The combination, with a centrifugal liquid-bearing rotor, of a series of fog generating semi-annular impact elements surrounding it, against which the liquid impinges; the said elements being arranged and adapted for their impact surfaces, at different elevations, to be progressively more 15 remote from the rotor's edge.

2. The combination, with a centrifugal liquid-bearing rotor, of a series of fog generating semi-annular impact elements surrounding it, against which the liquid impinges, arranged with the convex edges of 20 their semi-annular surfaces toward the rotor.

3. The combination with a centrifugal liquid-bearing rotor, of a series of impact elements surrounding it, each having a semi-annular flat surface against which the liquid impinges, arranged with the middle of its 25 curvature adjacent to the rotor and with its curvature extending thence to both sides of the plane of the rotor and outward from the 30 rotor in a radial plane thereof.

4. The combination with a centrifugal liquid-bearing rotor, of a series of impact elements surrounding it, each of semi-annular flat shape, against which the liquid impinges, mounted at one of its ends and curving 35 from said mounting inward toward the

edge of the rotor, past it and thence outward from it.

5. The combination, with a centrifugal liquid-bearing rotor, of a series of impact elements arranged close together around its edge, each said element having a portion extending progressively from the plane of impact thereon of liquid from the rotor, and progressively outward, from the axis of 45 the rotor, whereby heavy particles flying in direction away from said rotor are entrapped.

6. The combination, with a centrifugal liquid-bearing rotor, of a series of impact elements arranged close together in rows 50 around its edge with an open space between the said rows; the elements of one row being arranged close to the rotor's edge and constituting surfaces for initial impact of liquid, and the elements of the other row being set 55 back of the said initial impact elements and adapted to permit escape to atmosphere of fine particles of liquid but to arrest heavy particles and prevent their escape, as such, into the said atmosphere.

7. The combination, with a centrifugal liquid-bearing rotor, of a series of impact elements arranged close together around its edge, each element having a semi-annular flat surface, against which liquid from the 60 rotor impinges, arranged with respect to said rotor so that the liquid strikes its said flat surface substantially midway of its annular extent.
